SELECTIVE BLOCKING MEANS FOR A KEY OPERATED MACHINE

OBJECTS OF THE INVENTION

An object of the invention is to provide a device for selectively blocking actuation of the keys of a key operated machine in a simple and reliable manner and which may be easily installed.

Another object of the invention is to provide an apparatus mountable on a key operated machine for selectively blocking actuation of at least one key of said key operated machine when mounted therein which comprises a plurality of control means in cooperation with individual keys of said key operated machine for individually blocking actuation of said keys, said control means being biased in a key blocking position, a plurality of control rods, each cooperating with an associated control means, a first electromagnetic means moving said control rods collectively from a position of nonactivation of said control means to a position of activation of said control means, releaseable means for holding said control means in a key unblocking position, a plurality of movable blocking means in cooperation with said control rods to block movement of some of said control rods and a plurality of second electromagnetic means in cooperation with said movable blocking means to move said movable blocking means from a position blocking said control rod movement to a position unblocking said control rod movement whereby said control means in association with said control rods are activated to unblock actuation of said keys.

These and other objects of the invention will become more apparent as the description thereof proceeds.

THE DRAWING

FIG. 1 is a perspective cross section, parallel to the keys, of the key blocking device.

FIG. 2 is a plan view, partially cut away, of the key blocking device.

FIGS. 3 to 6 are exploded views of FIG. 1 showing details of the operation of the controls of the device.

DESCRIPTION OF THE INVENTION

I have now discovered a device for locking of keys for office machines. By means of this device all keys may remain unlocked so that the machine can be used in the normal way. Yet, on the other hand, all keys can be locked so that no actuation occurs whenever a key is struck. Furthermore, one key may be unlocked while all the other keys remain locked. Finally, a group of keys can be unlocked by means of the device of the invention whereby the keys belonging to one group are all unlocked at the same time so that they can be struck in any desired sequence while the keys which do not belong to this group remain locked. The unlocking of any group of keys, however, may as well be effected in that the individual keys of this group have to be struck in a certain sequence whereby the programming of the key sequence is arranged in such a way that only after actuation of the respective key, is the programmed next key unlocked.

The device of the invention serves substantially for teaching children as young as four years old how to type, particularly, how to type blindly, on typewriters and the like. Up to the present time, it has been customary to provide such instruction machines with colored markers for the keys which, however, has the disadvantage that the pupil has to look at the keys. By means of the device of the invention, the child can try all keys; however, only the right key can be activated, that is, the key which is not locked. The device of the invention is useful in cooperation with auxiliary devices to make appear the letter which is connected with this key on a screen and at the same time to have it announced over a loud speaker, that is, to have it transferred acoustically. The locking of all keys other than the desired one helps to avoid an impermissible act, namely, the actuation of the wrong key. From this, it is obvi-

ous that the child receives the information whether it does right or wrong while it seeks the desired letter which can be struck, and the others which cannot be struck, solely by the child's sense of touch.

Moreover, by means of the device it becomes possible to combine this basic stage with a further learning process, by having a preprogrammed group of keys struck one after the other. By actuating the right key, the next key of the sequence is caused to be unlocked and so forth. Thus words can be given which are written correctly since always the respectively next key is unlocked only upon the actuation of the previously chosen key. This instruction process causes the child, by means of the device of the invention, to spell words correctly due to the sequence of unlocking of the keys.

Finally, at a later stage of this learning process a group of keys can be unlocked so that the keys of this group can be operated arbitrarily. Hereby, it is provided that the child knows already in which sequence to strike the correct keys. Thus the child no longer receives the wrong signal with reference to the particular sequence of the keys of the unblocked group but all the other keys remain locked. Finally, optionally, all keys can be unlocked if the typewriter is to be used in the normal way.

The present invention is illustrated with the aid of the attached drawing which represents an exemplary embodiment of the present invention. As is shown in FIG. 1, the detent 1 rotates about its extension rod 1a and its extension, flange 7, on rotation extends into recess 6, prevents the key lever 3, terminating in a key 3b, being depressed between the guide jaws 2, from going all the way down, that is, it is locked. This happens when the accumulator member 4 in association with the particular key lever 3 does not hinder the rotation about its extension rod 1a of the detent 1 which is caused by the torsion spring 5, pressing on the flange 16 connected through extension rod 1a to the detent 1. Spring 5 on its part is attached prestressedly to the housing or guide jaws 2 and the flange 16 of the detent 1. This spring action causes the flange 7 of detent 1 to protrude from the recess 6 of the guide jaws 2 and locks

so that when the key lever 3 is pressed down on operation, the key lever heel 3a pushes against the protruding flange 7 of the detent 1. In locked position, protruding flange 7 abuts on both sides of the shoulders of recesses 6 which thus act as counter supports so that the flange 7 of the detent 1 will not be bent. A detent 1 is provided for each key lever 3 in side by side fashion under the machine. All of the accumulator members 4 can be displaced toward the right (FIG. 1) by turning the adjustment lever 10 clockwise in FIG. 1. Rotation of adjustment lever 10 causes rotation of the cam 8 shown in cross section 8a which rotates clockwise about fulcrum 62 in recess 60 in which is partially in solid bottom portion 20 and partially in the individual wall portions 20a (shown by dotted quarter circle of 60) of carrier element 20. The rotation of cam 8a about fulcrum 62 pushes against the shoulder 61 of accumulator member 4 and displaces the same to the right. Recess 9 in the accumulator members 4 allows this displacement to the right. Thereupon spring 11 is tensioned so that it can return cam 8 to its original position on release of adjustment lever 10.

The protruding accumulator member 4 is pushed against the lock bar 13 by means of spring 12 and, when displaced to the right, is locked with its recess 14 behind the edge 15 of the lock bar 13. Thus all displaced accumulator members 4 are kept in this locked position. At the same time they have pushed to the side the flanges 16 of the detents 1 and the protruding flanges 7 are turned into the recesses 6. Thus it becomes possible to depress the keys 3b of all the key levers 3 of the keyboard.

On the one hand the springs 12 push the accumulator members 4 against the edge 15 of the lock bar 13; on the other hand, they also act to push the accumulator members 4 into the locking position whereby they are shifted to the left, as is shown in FIG. 1. Springs 12 succeed in pushing the accumulator members 4 into the locking position the moment current passes through the electromagnet 17. At this time, the elec-

tromagnet 17 attracts the anchor 18, which is connected rigidly with the lock bar 13, against the tension of the spring 19. The lock bar 13 is turned and the edge 15 of the lock bar 13 slides out of the recesses 14 of the accumulator members 4, which are pushed back to the left by means of the springs 12. Thus the flanges 7 of the detents 1 can return from the recess 6 by means of the action of torsion spring 5 against flange 16 of detent 1, and in this way all key levers 3 are locked so that they can only be depressed if in the semidepressed position 47, from which results that none of the keys 3b of the key levers 3 can be depressed.

In each slot 48, which is in carrier element 20, one of which belongs to each key lever 3, as can be seen from FIG. 2, a control rod 21 and a pawl 22 are operatively engaged with the accumulator member 4. The pawls 22 are provided with two holes through which the two spindles 23a and 23b, common to all of the pawls 22, extend. These spindles 23a and 23b are movable inside the slot holes 24a and 24b.

Reference numeral 23 in FIG. 2 refers to the axes of spindles 23a and 23b.

FIGS. 3 to 6 illustrate the operation of the pawls 22. FIG. 3 illustrates in an exploded view the relationship of slot holes 24a and 24b within the carrier element 20 subdivided into a solid top portion 20c, a solid bottom portion 20b and individual wall portions 20a between each slot 48. Within the wall portion 20a are slot holes 24a and 24b. Control bars 29-34, discussed later, lie in opening 100 made up of cooperating slots in the solid bottom portion 20b and the individual wall portion 20a of carrier element 20. The solid bottom portion 20b of carrier element 20 contains individual slots 104 in cooperation with each pawl 22 and each individual wall portion 20a has an extension 70 extending downward therefrom, and adapted to mount lever 26 (not shown in FIG. 3) at pivot point 71. Only one or, at the most, several levers 26 are necessary since they act to engage spindle 23a which extends through the width of carrier element 20 as shown in FIG. 2.

The moment current passes through the release magnet 25, the lever 26 grasps with its guide slot 27, the spindle 23a and guides it through the slot hole 24b. At the same time, with all of the pawls 22, the other spindle 23b is guided through the respective slot hole 24a. Thus the pawls 22 are caused to move and turn as illustrated consecutively in FIGS. 4 to 6. The control rods 21 are preloaded and thus move down and push against the cams 28 of the control bars 29-34. Spring 65 maintains lever 26 in a biased relationship in reference to the magnet 25.

These bars 29-34 are provided with a plurality of cams 28 according to a dual code. Each control bar 29-34 can be moved by means of a control magnet 55 and a spring 55a exactly by half the distance between control rods 21. Depending upon whether one or several of the control bars 29-34 makes this switch step in a preprogrammed way by means of their respective control magnets 55, the location of the plurality of the cams 28 at one of the control rods 21 is such that, in a programmed manner, only one or several control rods 21 can drop through the slots 28a in all of the control bars 29-34.

In the arrangement shown in FIG. 1, this is the case, for instance, if the control bars 29 and 34 are switched. If, in addition, one of the other control bars 30 to 33 is switched, than the sequence cams 28, operating in that place, are pushed under the control rod 21 and thus a complete downward movement of the control rod 21 is hindered.

FIG. 2 indicates individual positions 35-39 of control rods 21. From the drawing, it is obvious that the control rod 21 which belongs to position 35 can only be moved downwardly if only control bar 29 and no other is switched. Thus, none of the other control bars 30-34 is switched. For position 36 the control bar 30 has to be switched. For position 37, the control bars 29 and 30 have to be switched. Thus, although the cam 28b of control bar 29 unlocks position 35, however, the cam 28c of the control bar 30 is pushed into position 35. In this way the way the control bars 29-34 cause an unquestionable selection of the control rods 21 for any switch position.

If, as is shown in FIG. 1, the control bars 29 and 34 are switched, then the control rod 21 moved down into position 42 upon the turning down of the pawl 22 which it reaches when the lever 26 is turned into position 43, as is indicated by the dotted lines, by means of the release magnet 25. If then the lever 26 keeps turning, then the pawl 22 is pushed with its forward edge 44 against the guide stud 45 of the control rod 21, engages into it, and pushes control rod 21 to the right. Control rod 21 on its part pushes the accumulator member 4 to the right until it locks with the recess 14 on the edge 15 of the lock bar 13. The accumulator member 4, however, turns detent 1 so that now the key lever 3, which is associated with it, is unlocked and can be moved down completely into position 46, effecting the striking of the type lever associated with it.

The current which passes through the release magnet 25 is turned off immediately so that the pawl 22 and thus the control rod 21 return to their resting position, shown in FIG. 1. By means of the repositioning of the guide bars 29-34, a further key lever 3 can be unlocked immediately.

If only one key lever 3 is to be actuated at a time, then prior to each new programming, the programmed accumulator member 4 must be released again by operation of the electromagnet 17. This can be done for instance, in that a new programming is released by means of an indicator, such as, for instance, a switch, or in the case of a magnet switch through approximation, through an optical barrier and the like on the carriage advancing mechanism of the typewriter carriage since the carriage advancing mechanism can only be actuated by depressing a previously programmed key lever 3.

The preceding specific embodiment is illustrative of the practice of the invention. It is to be understood, however, that other expedients known to those skilled in the art may be employed without departing from the spirit of the invention.

I claim:

35. An apparatus mountable on a key operated machine having a plurality of keys for selectively blocking actuation of at least one key of said key operated machine when mounted therein which comprises a plurality of control means each individual control means being in cooperation with an individual key of said key operated machine having a plurality of keys for individually blocking actuation of said keys, each of said control means being biased to a key blocking position and comprising a detent biased to a key blocking position and an accumulator member biased to a key blocking position, a plurality of control rods, each of said control rods being biased to a position of activation of said control means and being in cooperation with an individually associated control means, a first electromagnetic means for moving said control rods collectively from a position of nonactivation of said control means to a position of activation of said control means, releasable means for holding said control means in a key unblocking position, a plurality of movable blocking means in cooperation with said control rods to block said bias to a position of activation of said control means of some of said control rods and a plurality of second electromagnetic means in individual cooperation with said movable blocking means to move said movable blocking means from a position blocking said bias to a position of activation of said control means of said control rods to a position unblocking said bias to a position of activation of said control means of said control rods whereby said unblocked control rods are activated by said first electromagnetic means to unblock said bias of said control means biased in a key blocking position for individually blocking actuation of said keys.
40. The apparatus of claim 1 wherein said plurality of movable blocking means are control bars provided with a series of blocking cams and unblocking slots distributed according to a dual code.
45. The apparatus as defined in claim 1 wherein said releasable means for holding said control means in a key unblocking position is in cooperation with a third electromagnetic means for releasing said releasable means whereby said control means are biased to a key blocking position.
50. The apparatus as defined in claim 1 wherein said plurality of movable blocking means are control bars provided with a series of blocking cams and unblocking slots distributed according to a dual code.
55. The apparatus as defined in claim 1 wherein said releasable means for holding said control means in a key unblocking position is in cooperation with a third electromagnetic means for releasing said releasable means whereby said control means are biased to a key blocking position.
60. The apparatus as defined in claim 1 wherein said plurality of movable blocking means are control bars provided with a series of blocking cams and unblocking slots distributed according to a dual code.
65. The apparatus as defined in claim 1 wherein said releasable means for holding said control means in a key unblocking position is in cooperation with a third electromagnetic means for releasing said releasable means whereby said control means are biased to a key blocking position.
70. The apparatus as defined in claim 1 wherein said plurality of movable blocking means are control bars provided with a series of blocking cams and unblocking slots distributed according to a dual code.
75. The apparatus as defined in claim 1 wherein said releasable means for holding said control means in a key unblocking position is in cooperation with a third electromagnetic means for releasing said releasable means whereby said control means are biased to a key blocking position.
